UNITED STATES PATENT OFFICE

MATTHEW M. MERRITT, OF MIDDLETON, MASSACHUSETTS, ASSIGNOR, BY MESNE ASSIGNMENTS, TO THE TANNING PROCESS COMPANY, OF BOSTON, MASSACHUSETTS, A CORPORATION OF MASSACHUSETTS

MACHINE FOR TREATING HIDES, SKINS, AND LEATHERS

Application filed January 3, 1930. Serial No. 418,348.

This invention relates to machines for treating hides, skins and leather by means of treating liquids. While the invention is illustrated with reference to a machine for 5 tanning hides and skins it will be understood that the invention and various important features thereof may have other applications and uses.

As heretofore constructed, machines for 10 tanning hides and skins, other than those of the drum type into which hides or skins were thrown in a promiscuous mass, have comprised traveling or rotatable members carrying frames to which hides or skins were 15 attached at their edges while being subjected to the action of tanning agents. While the work in these machines received more uniform treatment than was possible in drums it was at the sacrifice of quantity production 20 and of speed in tanning. A machine which marks a distinct advance over machines of the types referred to is that disclosed in United States Letters Patent No. 1,694,447, granted Dec. 11, 1928, upon application of 25 M. M. Merritt. In this machine a lengthy conveyor is provided, the numerous slats or cross bars of which are adapted to carry many pieces of work for treatment at the same time, thus maintaining production at 30 a relatively high level. In order that the pieces of work in this machine may be introduced, while in extended condition, into a tanning solution and subjected to mechanical treatment to hasten the tanning there- 35 of, without likelihood of injury to the delicate grain surfaces of the hides or skins, a work supporting member or drum is pro- 40 vided between the upper and lower runs of the conveyor, the arrangement being such 45 that the pieces of work fold over the drum in superposed, overlapping relation to each other and are carried downwardly in this overlapped condition upon the surface of the drum in passing from the upper to the 50 lower run of the conveyor. In this way the hides or skins are repeatedly immersed in the tanning solution and as often withdrawn therefrom while under control to avoid damage to the grain surfaces of the hides or 55 skins. At the same time they are gently

flexed in passing around the cylindrical surface of the work supporting member or drum, thus facilitating the penetration of the tanning solution.

Objects of this invention are to improve generally tanning machines of the types mentioned above and, more particularly, to improve the machine of the patent to secure work of better quality than that produced heretofore by providing for even more efficient and careful handling of the hides and skins during the tanning operation.

To these ends, and in accordance with an important feature of the invention, means is provided for controlling the relative positions of a conveyor and of a work supporting member or drum, to which the conveyor carries pieces of work, to cause relative vertical movement between the pieces of work while they are approaching the work supporting member or drum at a time when they are hardly, if at all, in contact with each other. Hence, any slipping or overlapping movement that occurs at this time between adjacent hides or skins cannot cause injury because of the lack of contact, or of contact under pressure, between the surfaces of work pieces moving relatively to each other. When this relative movement takes place before they come into contact with each other and with the supporting surface of the supporting member or drum, the amount of movement which takes place after coming into contact with the supporting member is lessened by the amount of such prior movement and is reduced to a practical minimum. In the illustrated construction, the described means is embodied in guide members which serve to deflect the upper run of an endless conveyor downwardly toward a drum or other work supporting member located between the two runs of the conveyor and employed for introducing pieces of work in extended condition into tanning liquid in the bottom portion of a vat. By thus deflecting the upper run of the conveyor downwardly toward the work supporting member, the pieces of work are caused to move relatively to each other in a vertical direction and toward each other

100

in a horizontal direction before they contact with the work supporting drum or press upon each other, and in this way slipping of the pieces of work with respect to each other after they contact with each other and with the drum is minimized as far as practicable.

In order to obviate possibility of injury to hides or skins while they are coming off of the work supporting member or drum and starting along in the direction of the more or less straight path of the lower run of the conveyor, this portion of the conveyor, adjacent to the work supporting member in the illustrated machine, is deflected upwardly toward said member so that the hides or skins follow a path concentric with respect to the axis of the work supporting member or drum for a sufficient distance to insure that the rear end portions of the hides or skins drop away from each other and from the lower side of the drum and into the tanning liquor

in the vat, in this way becoming free to move without friction in relation to each other, before the forward ends of these same hides or skins start upon the more or less straight portion of their travel with the lower run of the conveyor. Because of this arrangement there is practically no relative slipping movement between the hides or skins while they are pressed firmly against each other upon the curved lower portion of the work supporting member or drum.

Hides and skins as commonly prepared for tanning are irregular in contour. In other words, each hide or skin has projecting shank portions and also other projecting portions or tabs that tend to fold upon themselves when the hide or skin is suspended, as for instance, from a slat of a conveyor or while resting in part over a cylindrical surface. If a tab or shank or other projecting portion be allowed to become wrinkled or folded during the tanning operation, the wrinkles or folds thus produced are apt to be permanent or removable only with difficulty in the succeeding finishing operations upon the hides or skins.

Hence, it is a further object of this invention to minimize the occurrence of such folding or wrinkling of the projecting portions of the hides or skins.

In order to obviate folding of shanks, tabs and other projecting portions of the hides or skins during passage over a work supporting member such as that provided in connection with the conveyor in the illustrated machine, the surface of the illustrated work supporting member is curved in a direction lengthwise of the member so that the shanks, tabs and other projecting portions tend to become straightened out in extended condition through the action of gravity thereon while they are resting upon inclined portions of the curved surface. In the illustrated construction, the work supporting member is shown as a bar-shaped circular member having both its

ends of a diameter substantially less than that of the median transverse diameter thereof, whereby inclined supporting surfaces are provided on the upwardly facing portions of the work supporting member.

These and other features of the invention will now be described in detail and then pointed out more particularly in the appended claims.

In the drawings,

Fig. 1 is a top plan view of a machine illustrating one embodiment of the invention, with portions broken away the better to disclose other parts within the machine, and

Fig. 2 is a longitudinal vertical section of the machine shown in Fig. 1.

In the illustrated machine, which is designed especially for the tanning of hides, there is provided a vat or tank 10 adapted to contain a body of tanning liquid suitable for the tanning of hides or skins. Preferably and as shown the vat or tank is provided with cover portions 12 having hinged doors 14 and 16 located at opposite ends of

the vat. Within the vat there is mounted a conveyor 18 consisting of spaced sprocket chains 20 joined by slats or rods 22 which

not only serve as parts of the conveyor but as elements to which the hides or skins may be attached. Each chain 20 comprises links 21, having pivotal connections 23 with each other, and each passes around a rear sprocket wheel 24 and a front sprocket wheel 26. Both sprocket wheels 26 are carried fixedly by a shaft 28 which is journaled in the side frames of the vat 10. The sprockets 24, however, are mounted independently of each other, each sprocket being carried by a trunnion or stub shaft 30 mounted in the adjacent frame work of the vat, so as to leave all of the space between the two sprocket wheels 24 unobstructed, the purpose being to permit the hides or skins to hang freely between the sprocket wheels 24 while being suspended from the upper run of the conveyor.

Mounted fixedly upon the shaft 28 is a drum 32 which extends the full distance between the sprocket wheels 26 and serves as a member movable with the conveyor to carry the hides or skins in extended condition as they pass from the upper run of the conveyor to the lower run thereof, whereby the hides or skins are introduced in extended condition and without any undue flexing into the tanning liquid in the lower part of the vat 10. As thus far described, the apparatus is similar to that disclosed in United States Letters Patent No. 1,694,447 mentioned in the earlier part of this specification.

As the hides or skins are carried along with the upper run of the conveyor, they hang suspended in spaced relation to each other in order that the tanning liquid may

drain from the surfaces preparatory to another immersion in the tanning liquid in the bottom of the vat. As the hides or skins, carried by the conveyor, approach the drum 32 they contact with each other and then pass over the drum in overlapped relation, in this way being kept in fully extended condition and gently flexed as above described. Where the upper run of a conveyor 10 extends in a substantially straight line or plane between the front and rear sprockets, there is a certain amount of slipping of the hides or skins relatively to each other during the first part of their folding over the 15 drum. The amount of slipping is not great in amount and is not particularly objectionable if the hides or skins be given a preliminary tanning before being placed in the machine. However, to minimize, as far as 20 practicable this slipping of the hides or skins with respect to each other as they come into contact with the drum, the upper run of the conveyor, in the illustrated machine, is deflected downwardly as it approaches the 25 drum. This downward deflection of the conveyor positions this portion of the conveyor at an inclination away from the horizontal and toward the vertical so that any given slat or rod moving into this portion of the 30 path of the conveyor moves vertically with respect to both the preceding and the following rod or slat. At the same time, the two last-mentioned slats or rods move closer to the plane passing vertically through the intermediate slat or rod. By reason of this fact 35 the hides or skins on these slats or rods are brought closer together and at the same time moved in vertical directions with respect to each other. Since, however, the hides or 40 skins at this time are not in contact with each other, or at least not pressing upon each other, the relative vertical movement between the surfaces of adjacent hides or skins 45 has no effect, deleterious or otherwise, although there might be an undesirable result if the surfaces, during such relative movement, were pressed firmly together as by the weight of a superposed mass of hides or skins. By having this relative vertical movement between the hides or skins take place 50 before they are in firm or pressing contact with each other, the amount of such relative movement which takes place after the hides or skins become overlapped above the drum 55 is reduced by the amount of such relative movement which takes place as described before they come into pressing contact with each other. For deflecting the upper run of the conveyor downwardly toward the drum 60 32 there are provided two stationary guide members 34 one at each side of the vat. These guide members 34 have their lower edges cam shaped to contact with the ends of the conveyor slats 22 or rods to guide the conveyor 65 and gradually deflect it toward the drum 70 32. It will be understood that the guide member 34 may be provided with any well known anti-friction means such as rollers to lessen the amount of friction between the conveyor and the guide members. While the 75 guide members 34 might be so shaped as to cause a greater deflection in the conveyor 20, it has been found that the degree of deflection shown in the illustrated machine accomplishes results sufficiently satisfactory and 80 that as a result of such deflection the slipping of the hides or skins relatively to each other is reduced to a practicable minimum. As the hides or skins are being carried along 85 by the conveyor in overlapped relation upon the lower portion of the drum 32, they tend to fall away from the surface of the drum so that the amount of friction between the pieces of work due to relative slipping movement between the hides or skins is not marked, the 90 said slipping taking place as the conveyor starts away from the drum on its straight run. However, to minimize the amount of slippage, guide members 36 are provided for deflecting the lower run of the conveyor upwardly toward the drum so that the hides or skins, moving in concentric relation with the drum for an additional distance, have dropped away completely from the drum before the said relative slipping movement 95 takes place. Furthermore, the hides or skins are at that time immersed and floating in the tanning liquid. For both of these reasons, any slipping movement between the pieces of work which takes place as the upwardly 100 bowed conveyor leaves the drum is so slight and under such lack of pressure that no deleterious effects are observable. The guide members 36 are stationary members fastened to the frame of the vat and providing cam shaped surfaces for contact with the ends of the slats or rods 22 to determine the path of the latter as they are leaving the drum 32. Since both the hides and skins are obtained 105 from round-bodied animals they do not lie flat in contact with a flat surface nor everywhere in contact with a cylindrical surface while passing over the latter as in the patented machine. Furthermore, each hide or skin is irregular in contour and has projecting shank portions, tabs and other projections which tend to fold upon themselves while the hide or skin is hanging in suspended relation to its supporting slat or rod of the conveyor. This tendency of the projecting 110 portions to sag and fold upon themselves is also noticeable while they are passing over a cylindrical surface such as that provided by the ordinary drum. To obviate this tendency which is more marked where the shank 115 portions are longest, the drum 32 in the illustrated machine is made barrel-shaped, that is, with each end of a smaller diameter than the transverse median diameter. In other words, there is provided a work support hav-

ing curved surfaces which are inclined with respect to the longitudinal axis of the work support. It has been found that as a result of the action of gravity in connection with the inclined surfaces of the barrel-shaped drum, the shanks and other projecting portions of the hides or skins are straightened out on the inclined surfaces and are therefore better supported and do not tend to fold upon themselves. The objection to portions of the hides or skins folding upon themselves is due to the formation of wrinkles as the result of folding, such wrinkles being then tanned in the hide or skin in such a way as to be more or less permanent or removable with difficulty in the finishing operations. By providing means which has the effect of lessening markedly the tendency of shanks and other projecting portions to fold upon themselves while on the work support, there has been effected a distinct improvement in machines designed for the tanning of hides or skins. In the operation of the machine shown in the drawings, the hides or skins travel along with the upper run of the conveyor in suspended condition which permits drainage of the tanning liquid from them until they reach the drum 32. Here they fold upon the drum in overlapped relation to each other being at the same time gently flexed to assist in the penetration of the tanning liquid. Continued movement with the conveyor finally leads the overlapped mass of hides or skins into the tanning liquid in the lower part of the vat where the hides or skins are again immersed and carried along on the upper surface of the lower run of the conveyor. As they leave the drum 32 they separate from each other and float in the tanning liquid which thus has a chance to act upon all of the surface of the hides or skins. As the hides or skins reach the front end of the vat, they are gradually lifted up from the tanning solution and suspended to drain with the surfaces of the hides or skins spaced at considerable distances from each other. This operation of immersing the hides or skins in the tanning liquid and then suspending them to drain only to be again immersed with gentle flexing of the hides or skins at each end of their travel results in relatively rapid tanning. The provision of means, as above described, for lessening the slipping of the hides or skins relatively to each other while they are in contact in overlapped relation, has resulted in lessened possibility of injury through friction between the various surfaces. Furthermore, in the provision of the barrel-shaped drum there is less likelihood of any folding of the shanks or other projecting portions of the hides or skins with the result that little or no wrinkles appear in these projecting portions. Both of these features contribute materially to secure a high quality of product in a ma-

chine which is especially adapted to secure rapid tanning of the pieces of work.

Having described my invention what I claim as new and desire to secure by Letters Patent of the United States is:

1. In a machine for treating hides and skins, a conveyor for supporting hides or skins in suspended relation thereto, means for movably supporting the conveyor, a work supporting member having a curved surface located in the path of the hides or skins suspended from the conveyor, and means constructed and arranged to determine the relative positions of the conveyor and of the curved surface of the work-supporting member to control the amount of overlap between adjacent pieces of work before they reach the work-supporting member.

2. In a machine for treating hides and skins, an endless conveyor having a lower run and an upper run, for supporting hides or skins in suspended relation to said upper run, a work-supporting member located between the upper and lower runs of the conveyor, rotary members at the ends of the conveyor for supporting the same, the upper run of the conveyor being arranged to move the pieces of work toward and upon the work-supporting member, and means constructed and arranged to position the upper run of the conveyor and the work-supporting member relatively to each other so that the upper run of the conveyor inclines away from the horizontal and toward the vertical in the portion adjacent to the work-supporting member whereby adjacent pieces of work as they enter the described inclined portion of the conveyor shift vertically relatively to each other.

3. In a machine for treating hides and skins, an endless conveyor having a lower and an upper run for supporting hides or skins in suspended relation to said upper run, a work-supporting member located between the upper and lower runs of the conveyor, rotary members at the ends of the conveyor for supporting the same, the conveyor being arranged to move the hides or skins suspended from the upper run toward and upon the work-supporting member, and means constructed and arranged to deflect the upper run of the conveyor with respect to the work-supporting member as the conveyor approaches the work-supporting member.

4. In a machine for treating hides and skins, an endless conveyor having a lower and an upper run for supporting hides or skins in suspended relation to said upper run, a work-supporting member located between the upper and lower runs of the conveyor, the conveyor being arranged to move the hides or skins suspended from the upper run toward and upon the work-supporting member, and means located above the conveyor to deflect the upper run of the conveyor in

- a direction toward the work-supporting member as the conveyor approaches the work-supporting member so that the pieces of work carried by the conveyor shift vertically relatively to each other as they approach the work-supporting member.
5. In a machine for treating hides and skins, an endless conveyor having upper and lower runs, members at the ends of the conveyor for supporting the same, a rotary member located between the upper and lower runs of the conveyor, the upper run of the conveyor being arranged to have pieces of work suspended therefrom and to move the pieces of work toward and upon the rotary member, and guide members arranged to deflect the upper run of the conveyor in a direction toward the rotary member as the conveyor approaches the member.
10. In a machine for treating hides and skins, a vat adapted to contain treating liquid, an endless conveyor, rotary members adjacent to each end of the vat for supporting the conveyor, the latter having upper and lower runs spaced from each other so that pieces of work suspended from the upper run clear the pieces of work resting upon the lower run, the lower run and pieces of work thereon being arranged to travel in the lower part of the vat and to be covered by the treating liquid, a rotary drum located at one end of the conveyor between the upper and lower runs thereof, and guide members located above the conveyor adjacent and parallel to the longitudinal edges thereof to bow the upper run of the conveyor in a downward direction as it approaches the drum so as to maintain the pieces of work carried by the upper run in lapping relation upon the drum for a longer time than would be the case if the upper run of the conveyor were left to follow a normal straight line path.
15. In a machine for treating hides and skins, a vat adapted to contain treating liquid, an endless conveyor for supporting pieces of work and having upper and lower runs, the lower run and pieces of work thereon being arranged to travel in the lower part of the vat, and to be covered by the treating liquid, members at the ends of the conveyor for supporting the same, a drum located between the upper and lower runs of the conveyor, the upper run of the conveyor having pieces of work suspended therefrom being arranged to move the pieces of work toward and upon the drum, and guide members positioned to bow the upper run of the conveyor in a direction toward the drum as the conveyor approaches the drum so that the pieces of work carried by the conveyor shift vertically relatively to each other as they approach the drum thereby lessening substantially such relative shifting after these pieces of work contact with each other and with the drum.
20. In a machine for treating hides and skins, a vat adapted to contain treating liquid, an endless conveyor having upper and lower runs, the lower run and pieces of work thereon being arranged to travel in the lower part of the vat, and to be covered by the treating liquid, members at the ends of the conveyor for supporting the same, a drum located between the upper and lower runs of the conveyor, the upper run of the conveyor having pieces of work suspended therefrom being arranged to move the pieces of work toward and upon the drum, and guide members positioned to bow the upper run of the conveyor in a direction toward the drum as the conveyor approaches the drum so that the pieces of work carried by the conveyor shift vertically relatively to each other as they approach the drum thereby lessening substantially such relative shifting after these pieces of work contact with each other and with the drum.
25. In a machine for treating hides and skins, an endless conveyor having upper and lower runs, a member having a curved work-supporting surface and located at one end of the conveyor between the upper and lower runs thereof, and guide members located above the conveyor and having a downwardly projecting portion to deflect the upper run of the conveyor downwardly toward the curved work-supporting surface to cause a substantial portion of the conveyor to travel in a path concentric to the curved work-supporting surface.
30. In a machine for treating hides and skins, an endless conveyor having upper and lower runs, a rotary drum located at one end of the conveyor between the upper and lower runs thereof, and guide members located above the conveyor and arranged to deflect the upper run of the conveyor with respect to the drum.
35. In a machine for treating hides and skins, an endless conveyor having upper and lower runs, a work-supporting member located between the upper and lower runs of the conveyor, and means constructed and arranged to determine the relative positions of the lower run of the conveyor and of the adjacent lower surface of the work-supporting member to control the amount of wrapping of the pieces of work upon the surface of said work-supporting member in their movement around the work-supporting member.
40. In a machine for treating hides and skins, an endless conveyor having upper and lower runs, rotary members at the ends of the conveyor for supporting the same, a work-supporting member located between the upper and lower runs of the conveyor, the upper run of the conveyor being arranged to move pieces of work toward and upon the work-supporting member, and means arranged to position the lower run of the conveyor and the work-supporting member relatively to each other so that the lower run of the conveyor, in the portion thereof adjacent to the work-supporting member, inclines away from the horizontal and toward the vertical.
45. In a machine for treating hides and skins, an endless conveyor having upper and lower runs, a rotary drum located at one end of the conveyor between the upper and lower runs thereof, and guide members located above the conveyor and arranged to deflect the upper run of the conveyor with respect to the drum.
50. In a machine for treating hides and skins, an endless conveyor having upper and lower runs, the lower run and pieces of work thereon being arranged to travel in the lower part

- of the vat, rotary members adjacent to the ends of the vat for supporting the conveyor, a work-supporting member located between the upper and lower runs of the conveyor, the upper run of the conveyor being arranged to move pieces of work toward and upon the work-supporting member, and means having a portion located below the conveyor and arranged to position the lower run of the conveyor and the work-supporting member relatively to each other so that the lower run of the conveyor, in the portion thereof adjacent to the work-supporting member, inclines away from the horizontal and toward the vertical.
14. In a machine for treating hides and skins, an endless conveyor having upper and lower runs, rotary members at the ends of the conveyor for supporting the same, a work-supporting member located between the upper and lower runs of the conveyor, the upper run of the conveyor being arranged to support pieces of work in suspended relation thereto and to move the pieces of work toward and upon the work-supporting member, and means constructed and arranged to deflect the lower run of the conveyor with respect to the work supporting member.
15. In a machine for treating hides and skins, an endless conveyor having upper and lower runs, a work-supporting member located between the upper and lower runs of the conveyor, the upper run of the conveyor being arranged to support pieces of work in suspended relation thereto and to move the pieces of work upward direction toward the work-supporting member thereby increasing the wrap of the conveyor and of the work pieces about the work supporting member.
16. In a machine for treating hides and skins, an endless conveyor having upper and lower runs, a rotary drum located between the upper and lower runs of the conveyor, the upper run of the conveyor being arranged to move the pieces of work toward and upon the drum, and stationary guide members positioned to extend the path of the lower run of the conveyor concentrically with respect to the drum.
17. In a machine for treating hides and skins, a vat adapted to contain treating liquid, an endless conveyor having upper and lower runs, the lower run and pieces of work thereon being arranged to travel in the lower part of the vat, a rotary drum located between the upper and lower runs of the conveyor, the upper run of the conveyor being arranged to move the pieces of work toward and upon the drum, and guide members located below the conveyor adjacent and parallel to the longitudinal edges thereof to deflect the lower run of the conveyor in a direction upwardly toward the drum thereby increasing the wrap of the conveyor and of the work pieces about the drum.
18. In a machine for treating hides and skins, an endless conveyor having upper and lower runs, a drum located at one end of the conveyor between the upper and lower runs thereof, and means constructed and arranged to deflect both the upper and lower runs of the conveyor toward each other to cause lapping of the pieces of work over a considerably greater portion of the periphery of the drum than would be the case if the runs of the conveyor were left each undeflected in straight line position.
19. In a machine for treating hides and skins, a vat adapted to contain treating liquid, an endless conveyor having upper and lower runs spaced from each other so that pieces of work suspended from the upper run clear the pieces of work resting upon the lower run, the lower run and pieces of work thereon being arranged to travel in the lower part of the vat, a drum located at one end of the conveyor between the upper and lower runs thereof, and guide members constructed and arranged to deflect both the upper and lower runs of the conveyor toward each other to cause lapping of the pieces of work over a considerably greater portion of the periphery of the drum than would be the case if the runs of the conveyor were left in undeflected straight-line position.
20. In a machine for treating hides and skins, an endless conveyor having upper and lower runs, and a member located between the runs of the conveyor and having a curved work-supporting surface, the upper run of the conveyor being arranged to have pieces of work suspended therefrom and to move the pieces over said curved surface, said curved surface having a portion inclined to the long axis of the work-supporting member at one end thereof.
21. In a machine for treating hides and skins, a vat adapted to contain treating liquid, an endless conveyor having upper and lower runs, the lower run and pieces of work thereon being arranged to travel in the lower part of the vat, and a circular member located between the runs of the conveyor and adapted to maintain the pieces of work in extended condition while they are being lowered into the treating liquid in the lower part of the vat, said member having one end of a diameter considerably smaller than that of the median transverse portion of the member.
22. In a machine for treating hides and skins, an endless conveyor having upper and lower runs to which pieces of work may be attached, and a movable member between the runs of the conveyor for supporting the pieces of work in extended overlapping re-

lation to each other while they are moving downwardly from the level of the upper run to that of the lower run of the conveyor, said movable member having its greatest diameter in the median transverse portion thereof and tapering toward each end.

23. In a machine for treating hides and skins, an endless conveyor having upper and lower runs to which pieces of work may be attached, and a drum located between the runs of the conveyor, adapted to have the pieces of work overlap upon a portion of the periphery thereof, and arranged to lower them in extended condition from the upper to the lower run of the conveyor, said drum having one end of a diameter considerably smaller than that of the median transverse portion of the drum.

24. In a machine for treating hides and skins, a vat adapted to contain treating liquid, an endless conveyor having upper and lower runs to which pieces of work may be attached, the lower run and pieces of work thereon being arranged to travel in the lower part of the vat and to be covered by the treating liquid, and a drum between the runs of the conveyor for supporting the pieces of work while they are moving downwardly into the liquid in the vat, said drum having its greatest diameter in a median transverse portion thereof and tapering toward each end.

In testimony whereof I have signed my name to this specification.
